UNITED STATES PATENT OFFICE.

JOHN G. LOCHNER, OF BROOKLYN, NEW YORK.

COMBINED CHAIR AND COUCH.

Application filed February 23, 1921. Serial No. 447,163.

To all whom it may concern:

Be it known that I, JOHN G. LOCHNER, a citizen of the United States, residing at Brooklyn, in the county of Kings and State 5 of New York, have invented certain new and useful Improvements in Combined Chairs and Couches, of which the following is a specification.

This invention has relation to articles of 10 furniture, and has for an object to provide a combination of two articles so designed as to be utilized separately and individually in one capacity, and to be suitably connected for use in another capacity in a manner to 15 be hereinafter set forth.

Another object of the invention is to provide a dual article of furniture of the character above set forth consisting of two articles of the chair type each of which is provided with adjustable backs so that the back of one of said articles may be lowered into a horizontal position and adjusted with reference to the seat of the other article to form a couch or reclining surface, with 25 means for permitting adjustment of the various articles in a manner to be herein-after set forth.

In addition to the foregoing this invention comprehends improvements in the 30 details of construction and arrangement of parts to be hereinafter described and particularly set forth in the appended claim.

In the accompanying drawings in which 35 similar and corresponding parts are designated by the same characters of reference throughout the several views in which they appear.

Figure 1 is a side view of one of the 40 articles of furniture.

Figure 2 is a side view of the second article of furniture showing the relative positions of the reclining back in dotted lines.

Figure 3 is a side view showing the connected articles of furniture.

With reference to the drawings, A indicates generally one article of furniture and B, the other. With reference to the article A which is shown in side elevation only it will be obvious that the reverse side is duplicate in construction and hence the elements hereinafter described should be duplicated. It consists of the seat portion 10 mounted in the front legs 11 and rear legs 12, the latter being curved or otherwise ornamented 55 according to taste. Horizontal upper and lower rails 13 and 14 respectively connect

the two front legs 11, the two rear legs 12 and also the legs 11 and 12 to form a rectangular enclosure more or less for the reception of a tray 15. The rails 13 and 14 60 are spaced vertically for the purpose set forth. The back portion consists of the side members 16 connected together at their upper ends, each of said side rails 16 having their lower ends offset laterally by means 65 of the extension 17 and said extension pivotally secured to the rear edge of the chair by means of the pivot 18. The chair back is thus mounted for movement from a substantially vertical to a horizontal position. 70

The article of furniture B consists of the seat portion 19 supported upon the front legs 20 and the rear legs 21. In a similar manner these legs are connected one to the other by means of the vertically spaced horizontal rails 22 and 23 for the reception of the tray 24. The back portion consists of the side rail 25 having the lateral offset extension 26 pivotally connected to the rear portion of the shaft by means of the bolt 80 27. Also mounted upon the upper end of each of the front legs 20 is the swinging arm 28, curved and ornamented to suit the taste. The upper end of each swinging arm is connected to the side rail 25 of the back 85 portion by means of the arm rest 29 of which two are provided. The members 28 and 29 are connected together and to the legs by means of the bolts 30 and 31 respectively. The rear end of each arm rest 29 is connected to the side rail 25 by means of the bolts 32. I also provide a pair of arcuate braces consisting of the strip 33 pivotally connected to the bolt 31 and extended downward and passing through clamping members 35 operated by thumb screws which may be loosened or tightened to grip the strip 33 and thus hold the parts in any relatively adjusted position. From the foregoing it will be seen that the back rest 25 90 100 may be tilted to any desired angle as shown in Figure 2, the brace and the pivoted members 28 and 29 forming a means for securing the back rest in any adjusted position.

In operation the back rest 16 of the article of furniture A is lowered down to a horizontal position as shown in Figure 3 and the back edge of the back rest is then placed against the front portion of the article of furniture B. The juncture of the seat portion 10 and 19 and the back portion 16 of the article of furniture A will thus form a re- 110

clining surface. In this manner these articles may be co-operatively connected to form a sleeping couch. The back rest 25 may be lowered or raised in any position desired forming a pillow or head rest. The trays 15 and 24 may be lowered by slightly loosening them from their supports as shown in Figs. 1 and 2 and utilized to contain bedding or the like.

10. With reference to the article A it will be seen that when the back is in an upright position it may be held by means of a sliding bolt 36 which is mounted upon the back and adapted to slide into a keeper which is mounted upon the base portion of the chair. When the back of said article of furniture is to be moved to a horizontal position to form a sleeping couch said back may be secured to the base portion of the article B by the provision of a curved spring finger 37 mounted upon the back and adapted to snap over a projection 38 secured to the front face of the base portion of the chair B. With the articles of furniture in the position shown in Figure 8 it is desirable that they be held against separation and to that end I provide a rod 39 which is horizontally slidable in a plate 40 mounted upon the base portion of the chair B and having a hook portion adapted to engage in an eye bolt 41 secured to the base portion of the chair A. When the articles of furniture are to be separately used the rod 39 may be slid backward underneath the body of the chair B.

From the foregoing it will be seen that I have provided a novel combination of articles of furniture which are ornamentally designed and intended to be utilized as separate articles of furniture, as chairs, and which may be co-operatively connected to form a sleeping couch. In this manner a double function of the combination is possible without detracting from the ornamental appearance or utility of these articles when used in any other capacity. Other uses and advantages will readily occur to those familiar with the art to which this invention appertains.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim.

Having thus described my invention what I claim as new and desire to secure by United States Letters Patent is:—

In combination, a pair of freely movable articles of furniture of the chair type, an angularly adjustable back mounted on the seat of one of said articles of furniture, an arm swingingly connected to the front portion of said seat, an arm rest normally horizontal and pivotally connecting said swinging arm with said back, an arcuate member connected to one end at the juncture of the swinging arm and the arm rest and adjustably connected at its other end to said seat for adjusting the inclination of said back, a projection secured to the front face of the base portion of said article of furniture, a swinging back mounted on the seat of the other article of furniture, a curved spring finger carried by said swinging back adapted to snap over said projection when the said swinging back is in its lowered horizontal position, and a connecting rod adapted to be slidably carried by one of said articles of furniture for engaging the other article of furniture to prevent their separation.

In testimony whereof I affix my signature.

JOHN G. LOCHNER. [L.S.]
